SAMPLE EXTRACTING TOOL

Horace T. Parsons, Corpus Christi, and
Sydney P. Martin, McAllen, Tex.

Application September 27, 1946, Serial No. 699,742

4 Claims. (Cl. 255—1.4)

1

Our invention relates to improvements in sample extracting tools for use especially, although not necessarily, in obtaining samples of fluid matter at the bottom of drilled holes.

The primary object of our invention is to provide a simply constructed, efficient tool for dropping into drilled holes and which is rendered operative by impact with the bottom of the hole to drive into said bottom, form a sealed off pocket therein, extract a sample of the fluid contents of the pocket for analysis after the tool is retrieved, and at the same time, determine gas pressure at the bottom of the hole.

Other and subordinate objects, also comprehended by our invention, together with the precise nature of our improvements, and the advantages thereof, will be readily understood when the succeeding description and claims are read with reference to the drawings accompanying and forming part of this specification.

In said drawings:

Figure 1 is a view partly in side elevation and partly in longitudinal section of our improved tool in a preferred embodiment thereof.

Figure 2 is a fragmentary view in longitudinal section drawn to a larger scale.

Figure 3 is a disassembled view in perspective of the plunger and parts carried thereby.

Figure 4 is a view in perspective of the firing head.

Figure 5 is a view in bottom end elevation of the tool.

Figure 6 is a fragmentary view in longitudinal section illustrating the valve for the gas discharge line.

Figure 7 is a view in transverse section taken on the line 7—7 of Figure 2, and

Figure 8 is a similar view taken on the line 8—8 of Figure 2.

Referring to the drawings by numerals, according to the preferred, illustrated embodiment of our invention, an elongated tool is provided comprising an outer, tubular, metal casing 2 provided with an upper end head section 3 threaded in said upper end, as at 4, to close the same. The head section 3 provides a means whereby the casing 1 may be dropped into a drilled hole, not shown, and retrieved, as well as for sealing the upper end of the casing 1. Fins, as at 5, are provided on said head section 3 adapting the same for attachment to any suitable dropping and retrieving apparatus, not shown.

A packing sleeve 6 is threaded, as at 7, at its upper end, into the lower end of the casing 1 to extend therefrom with an internal upper end

2

flange 8 and a gland nut 9 threaded into the lower end thereof, as at 10, said flange 8 and nut 9 confining between the same a series of packing rings 11 in said sleeve.

5 An endwise slideable plunger 12, shorter than the casing 1 and of relatively smaller diameter, is provided in said casing and sleeve 6 with a working fit in the flange 8, nut 9 and rings 11. The plunger 12 is slideable outwardly and inwardly of the casing 1 and packing sleeve 6 and is provided with a circumferential lower end flange 13 adapted to engage the gland nut 9 to limit inward movement of the plunger. A screw 14 in one side of the plunger 12 is adapted 10 to engage the flange 8 and limit outward movement of said plunger. In each limit of movement of said plunger 12, the same extends into the casing 1 beyond the packing sleeve 6 for a purpose presently seen.

15 20 An axial chamber 14, with an internal shoulder 15 therein, is formed in the upper end of the plunger 12, and which is adapted to be packed with an explosive charge, not shown, and closed by a removable bushing 16 seating on the shoulder 15 and having suitably fixed therein a detonator 17 the cap 18 of which is exposed at the upper end of said plunger.

25 A hollow cylindrical firing head 19, having a closed upper end, is slidably fitted over the upper end portion of the plunger 12, and which has suitably fixed in the closed end thereof an axial firing pin 20 designed to puncture the cap 18 to cause the detonator 17 to ignite the explosive charge, not shown, in the chamber 14. Diametrically opposite shear pins 21 in the lower end 30 of the firing head 19 fix the same on the plunger 12 with the firing pin 20 spaced slightly above the cap 18.

35 A helical expansion spring 22 in the casing 1, interposed between the closed end of the firing head 19 and a fixed disc 23 in the casing 1, urges said head and plunger 12 into said outward limit of movement. The disc 23 is apertured, as at 24, to permit passage of fluid therethrough for a 40 purpose presently apparent.

45 A longitudinally fluted spudding bar 25 extends out of the lower end of the plunger 12, in the axis thereof, with an upper end threaded, as at 26, into an axial socket 27 in said end of said plunger. 50 The spudding bar 25 is formed with a cruciform lower end cutting edge 28, and with an axial duct 29 therein adapted to discharge at its upper end into the socket 27 and having lateral inlet branches 30 adjacent its lower end.

55 A resilient gasket 31 with a concave bottom 32

surrounds the spudding bar 25 and is suitably fixed thereon with a metal washer 34 interposed between the same and the flange 13 of the plunger 12 and backed by said flange.

Reverting now to the plunger 12, a pressure relief duct 35 in said plunger extends from the chamber 14 to a pressure outlet relief valve 36 arranged to discharge radially out of the flange 13. A duct 37 in the plunger 12 extends from the socket 27 to one side of said plunger to open at one end upon said side of the plunger.

A gas pressure line 38 is threaded, as at 39, at one end through one side of the casing 1 above disc 23 and into a valve seat 40 in said casing, said pressure line 38 having a pressure gauge 41 on the other end thereof. An adjustable needle valve 42 is threaded through the other side of the casing 1 for engagement with the seat 39 to close off said line if desired.

Describing now the operation of our improved tool. The plunger 12 is normally extended out of the lower end of the casing into its outward limit of movement by the spring 22. In this outward limit of movement of said plunger 12, the open end of the duct 37 is closed by being located within the confines of the series of packing rings 11. The tool, with the parts thus positioned, is dropped into a drilled hole, not shown, the bottom of which is represented at 42 in Figure 2 in dotted lines. As soon as the spudding bar 25 strikes said bottom 42, the casing 1 under the impact of the blow, descends on the plunger 12 into its described outward limit of movement, as shown in Figure 2, and thereby compresses the spring 22. The compressed spring 22 then exerts sufficient pressure on the firing head 19 to cause the shear pins 21 to separate, thus permitting said head 19 to descend on the plunger 12 sufficiently to cause the firing pin 20 to puncture the cap 18, thus causing the detonator 17 to explode the charge, not shown, in the chamber 14. At this point, the explosion drives the plunger 12 downwardly, thus forcing the spudding bar 25 into the bottom 42 until the gasket 31 is compressed on said bottom and forms a seal around a pocket 43 formed in the bottom 42 by said bar. Fluid matter, not shown, in the pocket 43 passes upwardly through the spudding bar 25 by way of the duct 29 and into the casing 1 by way of the open end of the duct 37 which is now located about the flange 8 of the packing sleeve 6, as shown in Figure 2. Thus, a sample of fluid matter from the bottom of the hole is obtained which is sealed in the casing 1. This sealed condition of the sample is maintained when the tool 1 is lifted out of the hole by return of the plunger 12 into its normal outward limit of movement, as shown in Figure 1, and in which limit the open end of the duct 37 is again closed in the manner already described. The pressure of gas in the bottom of the hole is registered on the pressure gauge 41. The tool may be shipped with the sealed sample therein, for analysis after removing the head section 3. After the explosion takes place, the chamber 14 is evacuated of burnt gas and the like through the duct 35 and valve 36.

The foregoing will, it is believed, suffice to impart a clear understanding of our invention, without further explanation.

Manifestly, the invention, as described, is susceptible of modification, without departing from the inventive concept, and right is herein reserved to such modifications as fall within the scope of the appended claims.

What we claim is:

1. In a tool adapted to be dropped endwise into a drilled hole, a tubular casing, a plunger in said casing having a lower end extending out of the same and being endwise slidable inwardly and outwardly of the casing, means forming a seal between said plunger and casing, a spudding bar extending from the lower end of said plunger and adapted to engage the bottom of the hole to cause said plunger to move inwardly of said casing, means in said plunger and casing rendered effective by impact of said bar against the bottom of the hole to drive said bar into the bottom of the hole including an explosive charge in the plunger and spring-tensioned devices for opposing the force of the explosion in one direction, and means to pass fluid material through said bar and plunger into said casing.

2. In a tool adapted to be dropped endwise into a drilled hole, a tubular casing having a removable upper end closure section, a plunger in said casing having a lower end extending out of the same and being endwise slidable inwardly and outwardly of the casing, means forming a seal between said plunger and casing, a spudding bar extending from the lower end of said plunger and adapted to engage the bottom of the hole to cause said plunger to move inwardly of said casing, a spring in said casing opposing inward movement of said plunger and adapted to be compressed by such inward movement of said plunger, means in said plunger and casing rendered effective conjointly by impact of said bar against the bottom of the hole and compression of said spring to drive said bar into the bottom of the hole, and means to pass fluid material through said bar and plunger into said casing, the second mentioned means comprising an explosive charge containing chamber in said plunger, and means for exploding said charge including a firing head on the plunger slidable thereon under the influence of said spring and influenced by said spring to oppose impact of the explosion.

3. In a tool adapted to be dropped endwise into a drilled hole, a tubular casing having a removable upper end closure section, a plunger in said casing having a lower end extending out of the same and being endwise slidable inwardly and outwardly of the casing, means forming a seal between said plunger and casing, a spudding bar extending from the lower end of said plunger and adapted to engage the bottom of the hole to cause said plunger to move inwardly of said casing, a spring in said casing opposing inward movement of said plunger and adapted to be compressed by such inward movement of said plunger, means in said plunger and casing rendered effective conjointly by impact of said bar against the bottom of the hole and compression of said spring to drive said bar into the bottom of the hole, and means to pass fluid material through said bar and plunger into said casing, the second mentioned means including an explosive containing chamber in said plunger, a detonator for igniting the explosive and having a cap, and a firing head on the plunger slidable therein under the influence of said spring into engagement with said cap and influenced by said spring to oppose impact of the explosion.

4. In a tool adapted to be dropped endwise into a drilled hole, a tubular casing having a removable upper end closure section, a plunger in said casing having a lower end extending out of the same and being endwise slidable inwardly and outwardly of the casing, means forming a seal between said plunger and casing, a spudding bar

extending from the lower end of said plunger and adapted to engage the bottom of the hole to cause said plunger to move inwardly of said casing, a spring in said casing opposing inward movement of said plunger and adapted to be compressed by such inward movement of said plunger, means in said plunger and casing rendered effective conjointly by impact of said bar against the bottom of the hole and compression of said spring to drive said bar into the bottom of the hole, and means to pass fluid material through said bar and plunger into said casing, the second mentioned means including an explosive containing chamber in said plunger, a detonator for igniting the explosive and having a cap, a firing head on said plunger adapted to be slid thereon under the influence of said spring into engage-

ment with said cap and influenced by said spring to oppose impact of the explosion, and shearable pins connecting said firing head to said plunger.
